United States Patent Office

Des. 214,302
Patented June 3, 1969

214,302

PILLOW

Abe Lee Barber, P.O. Box 19121,
Oklahoma City, Okla. 73119

Filed Mar. 22, 1968, Ser. No. 11,091

Term of patent 14 years

Int. Cl. D6—02

U.S. Cl. D3—9

FIG. 1.

FIG. 3.

FIG. 2.

FIG. 4.

FIG. 6.

FIG. 5.

FIG. 4

FIG. 1 is a perspective view of a pillow showing my new design, and taken from above and in front;

FIG. 2 is a perspective view of the pillow taken from behind and below;

FIG. 3 is a plan view of the pillow;

FIG. 4 is a front elevational view;

FIG. 5 is a rear elevational view; and

FIG. 6 is a side elevation of the pillow.

I claim:

The ornamental design for a pillow, as shown.
